UNITED STATES PATENT OFFICE.

HENRY J. SCHNEIDER, OF ROCHESTER, NEW YORK.

SCRAPING DEVICE.

1,297,502.

Specification of Letters Patent. Patented Mar. 18, 1919.

Application filed August 22, 1918. Serial No. 251,001.

To all whom it may concern:

Be it known that I, HENRY J. SCHNEIDER, a citizen of the United States, and resident of Rochester, in the county of Monroe and 5 State of New York, have invented certain new and useful Improvements in Scraping Devices, of which the following is a specification.

The present invention relates to a machine 10 for scraping lugs on lead battery plates, and an object of the invention is to provide means by which a battery plate lug may be effectively scraped without producing any curling of or injury to the lug.

15 To this and other ends the invention consists of certain parts and combinations of parts, all of which will be hereinafter described, the novel features being pointed out in the appended claims.

20 In the drawings:—

Figure 1 is a plan view of a machine constructed in accordance with the present invention;

Fig. 2 is a side elevation of the machine;

25 Fig. 3 is an enlarged sectional view of the machine adjacent the scraping devices;

Fig. 4 is a detail view of the scraping head, showing the supporting mounting therefor;

30 Fig. 5 is a view similar to Fig. 6, showing the scraping devices operating on the lug; and

Fig. 6 is a sectional view on the line a—a, Fig. 3.

35 Battery plates made from lead are usually provided with lugs through which electrical connections are established with the plate. These lugs are required to be scraped in order to remove the oxidized surface which

40 interferes with the electrical connection. Generally, this scraping has been accomplished by hand which is not only slow work but tends to injure the lugs. According to this invention, a means is provided which 45 operates on a number of faces of the lug, preferably all four faces simultaneously in the direction of the length of the lug to clean the lug without producing any injury thereto or any curling thereof.

50 Referring more particularly to the drawings wherein is illustrated one embodiment of the invention, 1 indicates a support in the form of a table having a guide 2 thereon against which one edge of the plate 3 is brought while such plate is resting upon the

table 1. At the same time that the plate is brought against the guide 2 its lug 4 is projected beyond one side of the table for operation upon by the scraping devices.

The scraping devices in this instance comprise four scraping blades 5, 6, 7, and 8. The blades 5 and 6 coöperate with the wide sides of the lug 4, while the blades 7 and 8 coöperate with the narrow or edge sides of the lug 4. The blades 5 and 6 have their cutting edges arranged at opposite angles to each other, while the blades 7 and 8 are preferably at right angles to the longitudinal axis of the lug 4. By having the blades 5 and 6 at angles to each other, all tendency to produce curling of the lug 4, which would occur if the blades were parallel, is overcome. In operation, the blades 5 to 8, inclusive, are moved without engaging the lug 4 toward the base or inner end of the lug, 70 after which all blades are brought into engagement with the lug 4, and are then moved in the direction of the longitudinal axis of the lug, being simultaneously drawn over the four faces of the lug toward the free 75 end of the latter, thus cleaning such faces.

In the illustrated embodiment, all of the blades are supported on the reciprocating frame 9 guided at 10 on the bed 11 which, in this instance, is integral with the supporting table 1 and extends laterally from the latter. On this frame is a projection 12 formed with four recesses in which the inner ends of four arms 13, 14, 15 and 16 are secured, said arms being made of spring 85 material and extending in one and the same direction from the projection 13, their outer ends being provided, respectively, with scraping knives or blade clamps 17, 18, 19 and 20 for the respective knives or blades 90 5, 6, 7 and 8. Each knife may be held in its clamping head by a tapered pin 21 which has one face bearing against the knife and the other against the head, a nut 22 on the end of the tapered pin serving to hold the 100 latter firmly against the knife to bind the knife in the clamping head.

Normally the knives are held away from the lugs by the spring in the arm, said arms being guided in the ring frame 23 which 105 is secured by bolts 24 to the sliding frame or carriage 9. In order that they may be moved so as to engage the plate lug after the knives have been carried toward the base or inner end of the lug, a mechanism is pro- 110

vided which comprises, in this instance, an operating ring 24^a rotatably mounted on the ring 23 and held thereto by pins 25 on the ring 24^a, operating in the annular groove 26 in the ring 23. The operating ring 24^a is preferably provided with a plurality of cam surfaces 27 co-operating with a cam surface 28 on one of the clamps, said ring also having portions 29 concentric with the ring 10 which will permit a movement of the ring without producing any movement in the arms 13 to 16, inclusive. It is apparent that, when the ring 24^a is turned to cause the cam portions 27 to engage the portions 15 28, the arms 13 to 16, inclusive, will be moved toward each other to cause the knife blades to engage the plate lug and, when the ring 24^a is turned in the opposite direction, to cause the cam portions 27 to ride off the cam 20 portions 28 on to the concentric portions 29, the arms 13 to 16, inclusive, will separate the knife blades.

Movement of the operating ring 24^a may be effected in any suitable manner. In this 25 instance, a spring 30 is anchored on the carriage 9 and projects forwardly into sliding engagement with the lug 31 on the under side of the ring 24^a. This spring 30 normally tends to hold the ring 24^a in a central 30 position. The projection 31 is also provided with the operating projection 32, the opposite faces of which, as shown in dotted lines in Fig. 3, are beveled. This operating projection is, in turn, adapted to travel in a 35 trackway formed by an elongated projection 33, whose opposite ends are beveled, as shown in Fig. 3 in dotted lines. When the carriage 9 is moved so as to bring the knives at the inner end of the battery lug, the projection 32 will lie in advance of the projection 33, as shown in dotted lines in Fig. 3. On the rearward movement of the carriage 9 the beveled face of the projection 32, adjacent the forward beveled face of the 40 projection 33, will co-operate with such beveled face of the projection 33, and cause a turning movement of the ring 24^a sufficient to bring the knives into engagement with the plate lug. After this engagement is once 45 established, and during the continued movement of the knives toward the free end of the battery lug, the projection 32 will co-operate with one side face of the projection 33 and hold the knives in this scraping 50 position until the end of the battery lug is reached, after which the spring 30 will shift the ring 24^a so that the forward face of the lug 32 will be brought opposite the rear face of the lug 33, thus causing the knives to 55 move away from each other, and, upon the forward movement of the knives, the forward face of the lug 32 will co-operate with the rear face of the lug 33 and shift the ring 24^a, so that the concentric portions 29 will 60 co-operate with the cam portions 28, thus pro- 65

ducing no movement in the knife supporting arms 13 to 16, inclusive, until after the forward end of the lug 33 is reached, when the spring 30 will again act and shift the lug 32 in advance of the lug 33 so that the 70 scraping action will again take place on the return movement of the carriage 9.

Movement of the carriage 9 may be effected in any suitable manner. In this instance, a pitman 34 is pivotally connected 75 at 35 to the carriage 9, and has a ring 36 which surrounds an eccentric 37 on the shaft 38 to which a worm wheel 39 is secured. This worm wheel 39 is journaled on the base frame 11 and meshes with a worm 40 80 on a shaft 41, the latter being journaled on the base frame 11 above the shaft 38 and at right angles to said shaft 38, and carrying a clutch member 42 with which cooperates a clutch member 43, the two clutch 85 members normally being held separated by a spiral spring 44. The clutch member 43 is mounted upon the shaft 45 of the motor 46 and is adapted to rotate with the said shaft 45, and to move axially of said shaft, 90 so that it may be brought into engagement with the clutch member 42 in order that motion may be transmitted to the shaft 41 and through the latter to the carriage 9.

Control of the connection between the motor 46 and the scraping devices may be effected by the battery plate 3, and to this end a two-arm lever 47 is pivoted at 48 on the table 1 with one of its two arms provided with a projection 49 lying in the path 100 of the top edge of the battery plate, so that when the battery plate is moved on the table 1, to be positioned in the path of the scraping devices, such plate will engage the lug 49 and shift the lever 47 on its pivot 48. 105 As the lever shifts on its pivot, it produces a pulling action in the rod 50 which is pivoted at 51 to the opposite end of the lever 47, and is also pivoted at 52 to a lever 53 which, in turn, is pivoted at 54 to the base frame 110 11 and has a yoke 55 at its free end engaging within a grooved collar 56 on the clutch member 43. The pull on the rod 50 shifts the clutch member 43 into engagement with the clutch member 42 and causes the 115 scraping devices to operate. The operator of the machine should, after the scraping devices have passed beyond the end of the battery lug 4, remove the battery plate, and this action permits the spring 44 to separate 120 the clutch members 42 and 43, thus stopping the scraping devices and at the same time causing the projection 49 to be shifted, so that when another battery plate 3 is introduced on the table 1 and has its lug 4 projected into 125 the path of the scraping devices, the latter will again be operated to scrap such lug.

From the foregoing it will be seen that there has been provided a scraping means which effectively scrapes a plurality of faces 130

of a lug of a lead plate without injury to the lug and without producing any curling action in the lug. The scraping devices may be adjusted readily to lugs of different sizes and 5 they are controlled through the battery plate, the introduction of the battery plate in a certain position on the machine automatically starting the scraping devices into action, which action automatically stops when the 10 operator removes the battery plate from the machine.

What I claim as my invention and desire to secure by Letters Patent is:—

1. A machine for scraping lugs of battery 15 plates embodying supporting means for the battery plates, scraping devices adapted to operate simultaneously on longitudinally-extending faces of a lug of a battery plate in the direction of the length of such lug, 20 mechanism for reciprocating said devices in the direction of the length of the lug, and mechanism for automatically separating said devices at a certain point in their movement to permit the lug to be introduced between 25 them.

2. A machine for scraping lugs of battery plates comprising supporting means for the battery plates, scraping devices for operating simultaneously on opposite faces of a lug of a 30 battery on the supporting means, and means for automatically effecting a relative movement between said devices to permit the introduction of a lug between them.

3. A machine for scraping lugs of battery 35 plates comprising supporting means for the battery plates, and scraping knives for operating simultaneously opposite each other on opposite sides of a lug of a battery plate on said supporting means, said knives being arranged with their cutting edges at angles to each other and to the longitudinal axis of the lug on which they operate.

4. A machine for scraping lugs of battery 45 plates embodying supporting means for the battery plates, two scrapers arranged to operate simultaneously on opposite longitudinal sides of a lug, said scrapers having their scraping edges inclining in opposite directions, mechanism for reciprocating said 50 scrapers in the direction of the length of the lug, and mechanism for separating said scrapers at a certain point in their movement to permit the lug to be introduced between them.

5. A machine for scraping lugs of battery 55 plates embodying supporting means for the battery plates, four scrapers movable simultaneously in opposite directions longitudinally of the lug, and mechanism for causing said scrapers to move toward each other to engage the lug when the scrapers are at the inner end of the lug and away from each other after the scrapers reach the outer end of the lug.

6. A machine for scraping lugs of battery

plates comprising supporting means for the battery plate, a reciprocatory carriage, spring arms on the carriage, scrapers carried by said arms, and mechanism for moving said scrapers toward each other at one end of the movement of the carriage and away from each other at the other end of the movement of the carriage.

7. A machine for scraping lugs of battery plates comprising supporting means for the battery plates, a reciprocatory carriage, spring arms on the carriage, scrapers carried by said arms, and mechanism for moving said scrapers toward each other at one end of the movement of the carriage and away from each other at the other end of the movement of the carriage, said mechanism comprising a rotary cam shifted at opposite ends of the movement of the carriage.

8. A machine for scraping lugs of battery plates comprising supporting means for the battery plates, a plurality of scrapers arranged to operate simultaneously on longitudinal sides of a lug, means for reciprocating said scrapers, and means for moving the scrapers toward each other when the latter reach one end of their movements and for effecting the movement of the scrapers away from each other when said scrapers reach the other end of their movement.

9. A machine for scraping the lugs of battery plates comprising supporting means for the battery plates, a reciprocatory carriage, spring arms on the carriage, scrapers supported by said spring arms to operate simultaneously on a plurality of longitudinal sides of a lug, a rotary cam for effecting the movement of the scrapers toward and from each other, and a switch device acting on said cam to control the movement of the cam.

10. A machine for scraping lugs of battery plates comprising supporting means for the battery plates, a reciprocatory carriage, spring arms on the carriage, scrapers carried by the arms to operate simultaneously on longitudinal sides of a lug, a rotary cam movable with the carriage to effect the movement of the scrapers toward and from each other, a projection on the cam, and a stationary switch arranged to cooperate with said projection for effecting the movement of the cam in opposite directions.

11. A machine for scraping lugs of battery plates comprising supporting means for the battery plates, a reciprocatory carriage, spring arms on the carriage, scrapers carried by the spring arms co-operating simultaneously on longitudinal sides of a lug, a rotary cam on the carriage for effecting the movement of the scrapers toward and from each other, a lug on the cam, a stationary lug with which said lug on the cam co-

operates, and a spring acting on the cam to cause the latter to shift slightly at opposite ends of the movement of the carriage.

12. A machine for scraping lugs of battery plates comprising supporting means for the battery plates, a reciprocating carriage, spring arms on the carriage, scrapers carried by the spring arms to operate simultaneously along longitudinal sides of the lug, a stationary ring on the carriage in which said spring arms are guided, a cam ring mounted to turn on the stationary ring, and means for shifting said cam ring at opposite ends of the movement of the carriage to effect the movement of the scrapers toward and from each other.

13. A machine for scraping battery lugs comprising supporting means for the battery plates, movable scraping means, a clutch controlling the starting and stopping of said scraping means, a support for the battery plate, means for controlling said clutch having a portion arranged to be engaged by a

battery plate when the lug on the latter is presented to the scraping devices.

25

14. In a machine for scraping lugs of battery plates, the combination with supporting means for the battery plates and scraping devices for operating simultaneously on longitudinal sides of a lug of a battery plate, of mechanism for operating said scraping devices embodying a clutch, a support for the battery plate, and controlling means for the clutch comprising a two-arm lever having a portion arranged to be engaged by the battery plate when the latter is presented to the scraping devices, a clutch lever connected to the clutch for shifting the latter, and a connection between said clutch-lever and the two-arm lever whereby when the battery plate is presented to the scraping devices the clutch lever will be shifted to cause the clutch to operate to effect the movement of the scraping devices.
